UNITED STATES PATENT OFFICE.

ALICE N. PRINGLE, OF PRESTON, CANADA.

DESIGN FOR A PAINTER'S CABINET.

SPECIFICATION forming part of Design No. 26,332, dated November 24, 1896.

Application filed September 21, 1896. Serial No. 606,599. Term of patent 7 years.

To all whom it may concern:

Be it known that I, ALICE N. PRINGLE, a subject of the Queen of Great Britain, residing at the village of Preston, in the county 5 of Waterloo and Province of Ontario, Canada, have invented and produced a new and original Design for China-Painters' Cabinets, of which the following is a specification, reference being had to the accompanying drawings, showing the invention.

The object of my invention is to devise a convenient and handsome cabinet particularly adapted for the use of china-painters; and it consists, essentially, of a cabinet constructed substantially of the shape and appearance shown in the accompanying drawings and hereinafter more specifically described.

Figure 1 is a perspective view of the cabinet closed. Fig. 2 is a perspective view with the well opened, the sliding table in position for use, and the hinged leaf raised.

My invention consists of a cabinet of about the following proportions: two feet nine 25 inches high, three feet three inches wide, and nineteen inches deep, provided with a drawer A at the bottom, and a well B, located above the said drawer, which is closed by a front C, which represents drawer-fronts, as indicated.

30 Above this is located a sliding table D, while

the whole cabinet is closed by the top F, which is divided in two parts connected together and provided with a flap G, adapted to close the front of the cabinet above the sliding table D. The central well is provided, as shown, with pigeon-holes and shelves or drawers.

The cabinet is also provided with a leaf I, which may be held in place by a suitable bracket.

40 The drawer A, front C, and sliding table D are provided with suitable pulls of ornamental construction.

The whole cabinet is set on casters and handsomely finished in natural wood, var- 45 nished, and polished.

On reference to the drawings it will be seen that I have devised a handsome and useful form of cabinet adapted for china-painters' use, the various compartments being specially designed for the storage of the 50 various articles needed in painting.

What I claim is—

The design for a painter's cabinet as herein shown and described.

Dated this 17th day of September, 1896.

ALICE N. PRINGLE.

In presence of—

I. J. KINGMILL,
FRED G. KING.
